UNITED STATES PATENT OFFICE

2,665,761

BACK SCUTTLING VALVE

Frank E. O'Neill, Los Angeles, and Mordica O. Johnston, Glendale, Calif., assignors, by mesne assignments, to Johnston Testers, Inc., Houston, Tex., a corporation of Delaware

Application December 12, 1949, Serial No. 132,482

5 Claims. (Cl. 166—4)

1

This invention relates to an oil tool, and particularly pertains to a back scuttling valve.

In oil well production, and particularly in connection with oil well formation tests, the fluid yielded by a well may accumulate excessive pressure and in order to prevent a blowout in the well it is desirable to impose the pressure of the hydrostatic head of the well upon the fluid which is flowing through the well string. Such an operation must be performed quickly and it is the principal object of the present invention to provide a tool which may be readily manipulated from the top of the well and which would make it possible for the hydrostatic head of fluid in the well to be imposed upon the connate fluid flowing from the formation.

The present invention contemplates the provision of a housing structure which may be mounted upon a suspending member such as a formation tester and which may be manipulated to permit the hydrostatic head of fluid in the well to flow downwardly into the structure and to flow upwardly as desired.

The invention is illustrated by way of example in the accompanying drawing in which:

Figure 1 is a view in elevation showing the application of the present invention.

Fig. 2 is an enlarged view in longitudinal section showing the back scuttling valve as indicated on the line 2—2 of Fig. 1.

Fig. 3 is a view in transverse section as seen on the line 3—3 of Fig. 2 showing the valve construction.

Referring more particularly to the drawing, 10 indicates a supporting string of pipe from which a formation tester is suspended. This tester usually carries a packer 13 of the sleeve or rathole type. It is usual to mount a trip valve 12 at the lower end of the supporting string 10 and to attach it above the formation tester so that when it is opened free access of fluid will be provided through the tester and into the supporting string. The trip valve is usually operated by dropping a go-devil into the supporting string and opening the valve. The lower end of the packer structure 13 carries a perforated anchor 14 through which connate fluid may flow from the well. In the present instance a back scuttling valve 15 is provided. It is interposed between the trip valve 12 and the formation tester 11 and is supported by the trip valve structure 12.

By reference to Fig. 2 of the drawing it will be seen that the supporting member is provided with a sub 16 at its upper end and receives a cylindrical tubular housing 17. This housing is perfo-

2

rated throughout its walls as indicated at 18. The housing is threaded onto the sub as shown at 19, and the sub in turn is formed with an internal threaded portion 20 to receive a mandrel 21. The mandrel 21 is threaded into the bore 20 and is formed with a central opening 22 which communicates with a bore 23 of the sub 16. The mandrel 21 is formed at its lower end with a thread which extends into a threaded bore 24. This bore is formed in a lower sub 25 to which a tester 11 or drill pipe is connected. The lower sub has an opening 26 in communication with the opening 22 which extends longitudinally through the mandrel. Mounted upon the mandrel 21 is a valve element 27 having a bore 28 through which the mandrel 21 extends. The valve element includes a cylindrical sleeve 29. As shown in Fig. 3 of the drawing the sleeve structure is formed with a plurality of longitudinally extending fins 30, the outer faces of which are slightly spaced from the interior of housing 17. Fluid may pass between these fins. The upper end of the sleeve 29 is fitted with a threaded bore 31 which receives a thread 32 formed on the mandrel 21. The thread 32 is relatively coarse and is cut left-handed so that the joints of the supporting elements will not be unscrewed when the supporting string is rotated to the right. Formed in the wall of the bore 28 beneath the threaded section 31 is a plurality of annular grooves 33 which receive packing rings 34. These form a suitable fluid-tight packing between the mandrel 21 and the wall of the bore 28. At the lower end of the sleeve 29 are similar grooves 35 which receive packing rings 36. These form a fluid-tight seal at the lower end of the sleeve and prevent upward flow of fluid. In the space between the packing rings the bore 28 is relieved, as indicated at 37, so that the sleeve 29 may move readily along the mandrel. Formed diagonally through the wall of the mandrel 21 and leading from the passageway 22 to the relieved portion of the bore 37 are back scuttling passages 38 which are opened when the sleeve 29 is moved to its lowermost position, as will be hereinafter described.

In operation of the present invention, the back scuttling valve is constructed and assembled as shown in the drawing and is connected as indicated in Fig. 1. It will be submerged in the fluid of a well so that the hydrostatic fluid under pressure may flow into the perforations 18 of the housing. The hydrostatic pressure will act against the fins 30 to resist rotation of the sleeve 29 so that when the central mandrel 21 is rotated, rotation of the sleeve 29 will be resisted. The

thread 32 on the mandrel 21 may then be unscrewed from the thread 31 so that eventually the sleeve 29 will be detached from the mandrel and will fall downwardly along the mandrel and into the housing 17. The sleeve 29 will also pass over the inclined ports 38 in the mandrel 21 allowing them to be free and open so that hydrostatic fluid may force its way upwardly through the passageway 22 and the passageway 23 in the supporting string, or pressure or pump suction may be exerted to create circulation of fluid within the housing and the passageway 23 of the supporting string.

It will thus be seen that the structure here disclosed provides simple means for preventing back scuttling and for creating a back scuttling flow for any purpose, as manipulated from the top of the well.

While we have shown the preferred form of our invention as now known to us, it will be understood that various changes may be made in combination, construction and arrangement of parts by those skilled in the art, without departing from the spirit of the invention as claimed.

Having thus described our invention, what we claim and desire to secure by Letters Patent is:

1. A back scuttling valve comprising a tubular valve housing having a port formed therein for admitting fluid to within the housing, a tubular sub connected to each end of the housing for connection to opposed sections of drill pipe or the like, a tubular mandrel disposed within the housing and connected at its opposite ends to the subs and having the interior thereof communicating with the interiors of the subs, said mandrel having a port formed therein, a sleeve slidably mounted on and threadedly engaging the mandrel and covering the port in the mandrel when in its initial position and adapted to be submerged in the fluid admitted by the port in the housing, and means on the sleeve resisting rotary movement of the sleeve relative to the fluid in which it is submerged operable upon rotation of the drill string to retard rotary movement of the sleeve and thereby cause threading of the sleeve along the mandrel to uncover the port in the mandrel.

2. A back scuttling valve comprising a tubular valve housing having a port formed therein for admitting fluid to within the housing, a tubular sub connected to each end of the housing for connection to opposed sections of drill pipe or the like, a tubular mandrel disposed within the housing and connected at its opposite ends to the subs and having the interior thereof communicating with the interiors of the subs, said mandrel having a port formed therein, a sleeve slidably mounted on and threadedly engaging the mandrel and covering the port in the mandrel when in its initial position and adapted to be submerged in the fluid admitted by the port in the housing, and radial fins on the sleeve terminating short of the interior of the housing for resisting rotary movement of the sleeve relative to the fluid in which it is submerged operable upon rotation of the drill string to retard rotary

movement of the sleeve and thereby cause threading of the sleeve along the mandrel to uncover the port in the mandrel.

3. A back scuttling valve comprising a tubular valve housing having a port formed therein for admitting fluid to within the housing, a tubular sub connected to each end of the housing for connection to opposed sections of drill pipe or the like, a tubular mandrel disposed within the housing and connected at its opposite ends to the subs and having the interior thereof communicating with the interiors of the subs, said mandrel having a port formed therein, a sleeve slidably mounted on and threadedly engaging the mandrel and covering the port in the mandrel when in its initial position and adapted to be submerged in the fluid admitted by the port in the housing, the exterior of the sleeve being irregularly formed for resisting rotary movement of the sleeve relative to the fluid in which it is submerged and cause threading of the sleeve along the mandrel to uncover the port in the mandrel when the device is rotated.

4. A back scuttling valve comprising a tubular mandrel having a port formed therein, a tubular housing surrounding the mandrel and having a port for admitting fluid to within the housing means for mounting the housing on the mandrel in spaced relation with respect to the mandrel, a sleeve slidably mounted on and threadedly engaging the mandrel and covering the port in the mandrel when in its initial position and adapted to be submerged in the fluid admitted to within the housing and means on the sleeve resisting rotary movement of the sleeve relative to the fluid in which it is submerged operable upon rotation of the device to retard rotary movement of the sleeve and thereby cause threading of the sleeve along the mandrel to uncover the port in the mandrel.

5. A back scuttling valve comprising a tubular mandrel having a port formed therein, a tubular housing surrounding the mandrel and having a port for admitting fluid to within the housing, means for mounting the housing on the mandrel in spaced relation with respect to the mandrel, a sleeve slidably mounted on and threadedly engaging the mandrel and covering the port in the mandrel when in its initial position and adapted to be submerged in the fluid admitted to within the housing and radial fins on the sleeve terminating short of the interior of the housing for resisting rotary movement of the sleeve relative to the fluid in which it is submerged operable upon rotation of the drill string to retard rotary movement of the sleeve and thereby cause threading of the sleeve along the mandrel to uncover the port in the mandrel.
